UNITED STATES PATENT OFFICE.

BENJAMIN PURNELL, OF BENTON HARBOR, MICHIGAN.

AUTOMATIC FLUSHING DEVICE.

1,274,195.

Specification of Letters Patent. Patented July 30, 1918.

Application filed December 24, 1917. Serial No. 208,642.

To all whom it may concern:

Be it known that I, BENJAMIN PURNELL, a citizen of the United States, residing at Benton Harbor, in the county of Berrien and State of Michigan, have invented a certain new and useful Automatic Flushing Device; and I do hereby declare the following to be a full, clear, and exact description of the invention, such as will enable others skilled in the art to which it appertains to make and use the same.

My invention is particularly adapted to automatically control the water for flushing water closets. The objects of my invention are: first, to provide a flushing device which may be operated noiselessly; second, to eliminate from the device all water tanks or reservoirs so objectionable on moving trains, boats, and crowded places; third, to obtain frost proof construction of a flushing device, suited to the requirements of outdoor closets; fourth, to secure immunity for the device from corrosion or clogging due to any foreign matter in the supply water; fifth, to provide such construction that the amount of water passed at an operation may be readily adjusted; sixth, to afford facilities for ready accessibility of all parts; seventh, to design a flushing device with the economy of manufacture in view, and, eighth, to render the device entirely automatic.

I attain these objects by the mechanism illustrated in the accompanying drawings, in which—

Figure 1 is a vertical section of the device; Figs. 2 and 3, horizontal sections on the lines A—A and B—B respectively of the casting 1; and Figs. 4 and 5, side and top views respectively of the device.

Similar numerals refer to similar parts throughout the several views.

The casting or body 1 is bored to receive the barrel 2 which may move axially therein and is also tapped to receive the stuffing box 3, which is in turn tapped to receive the gland 4, through which valve stem 5 operates. The said valve stem is screwed into the head 6 and locked by pin 7, which head is in turn screwed into the lower end of barrel 2 and hermetically sealed. The said barrel 2 is tapped at its upper end to receive the internal nut 8, and said barrel is partly filled with oil and contains the piston 9, which piston is in turn fitted to receive the valve disk 24 having a groove 27, and the flat sided guide 25 and this guide is loosely held

in said piston by the washer 11 and the pin 12; and the spring 13 tends to keep the seat in said piston up against said disk. The head 14 is screwed into the casting 1 and serves as a stop for the nut 15 screwed into the valve stem 10 which nut limits the downward travel of stem 10. The upward travel of stem 10 is regulated by nut 16 which engages the lever 17 and said lever is pivotally attached by the pin 18 to the casing 1 and has a lug 26 properly disposed thereon. The valve disk 22 is adapted to close on the seat 23.

This device, when operative, is attached to a closet bowl at C and a water supply at D and should have a suitable bowl seat pivoted on the pin 18 adapted to engage the lug 26 of lever 17, thereby holding the stem 10 in its upper position when said seat is resting on said bowl.

A cycle of operation of the device may be explained as follows—

The position shown in Fig. 1 is taken as initial. The lever 17 is so proportioned that in this position its lug 26 may engage a suitable bowl seat (which is not shown, and is the subject matter for a subsequent patent) and hold said seat in a position inclined from the horizontal. The stem 10, in this position, is held with its nut 15 resting on the head 14 by the spring 20 which is compressed between the head 14 and the washer 21, and the spring 19 reacting between washer 21 and the internal nut 8 holds the barrel in its upper position, and, through stem 5, it holds the disk 22 against its seat 23 keeping the water passage at D closed.

When the automatic flushing device, in its initial position, has the required pressure applied to the aforementioned bowl seat, as by a person sitting thereon, to bring said seat to its horizontal position, the lug 26 of lever 17 engaging said bowl seat will lift the disk 24, by means of nut 16 and stem 10, from its seat in the piston 9 as far as the washer 11 and the pin 12 will allow; and further movement of said lever will lift the piston 9 creating a vacuum below it which will be filled by the oil from above said piston rushing under the raised disk 24 and by the flat sides in the guide 25 and the holes in the washer 11. When the said bowl seat rests on said bowl the stem 10 has reached its upper position, the spring 13 will raise the piston 9 until its seat rests against disk 24 as the guide 25, disk 24, spring 13, pin 12,

washer 11, and piston 9 constitute a check valve. This might be termed the "set" position of the device.

When the aforementioned pressure is removed from the lug 26 of lever 17 as by a person arising from said suitably attached bowl seat, the pressure of the heavy spring 20 is released against the disk 24 and the piston 9, which pressure is communicated by means of the entrapped oil to the disk 22 through the intermediary of the barrel 2, the head 6 and the stem 5; and this pressure forces disk 22 down from its seat thereby opening the passage for water from the supply at D. This is the flushing position of the device.

When the barrel 2 is pressed down as described to the flushing position the compressed spring 19 reacting between the washer 21 and the nut 8 lifts the said barrel gradually, and forces the oil through the bypass 27 in the disk 24, which brings the valve disk 22, through its intermediate connections, back up to its seat 23 thereby closing the water passage from the supply.

The amount of water passed in one cycle from the supply to the bowl depends on how quickly the valve at D closes which in turn is dependent on two things; first, the size of the groove 27, which fixes how rapidly the oil may bypass from below piston 9 to above it; and, second, on how far the piston 9 is raised from its "initial" to its "set" position, which in turn is readily regulated by adjusting the nut 16.

A freer explanation of its operation, if allowable is that it is so constructed that it may have a bowl seat attached at C so that when the device is in a set position said seat rests on said bowl and when in its initial position said seat will be slightly raised. Now if the device is in its initial position and a person sits on said bowl seat it will raise the plunger 9 and compress springs 19 and 20 and allow the oil in barrel 2 to flow below said plunger; and, when such person rises the released spring 20 raises said seat and as aforescribed opens the valve at D allowing a quantity of water to pass when said valve is closed by the oil below piston 9 by-passing and allowing the spring 19 to gradually close said valve at D which brings the mechanism to its initial position. It is readily seen that if the nut 16 is screwed up, then the piston 9 will not be raised so high with a given movement of lever 17 and consequently since it does not raise as high there will not be so much oil go below it, and when lever 17 is released said oil is more quickly by-passed, and therefore the valve at D is closed quicker, and less water is passed; and, the converse is true when nut 16 is screwed down, thus the amount of water passed at one flush may be conveniently regulated.

From Fig. 1 it is apparent that the valve at D may be any desired distance below the remainder of the mechanism and said valve fitted with a drain, if it is desired to make the device frost proof; but this is the subject for a separate patent, it is desired only to show here that this mechanism lends itself to outdoor use in cold climates and to have its water valve below the frost line.

It is to be noted that all movements are oil cushioned and that the valve closure is gradual, and, therefore the device must of necessity be quiet. As the bottom of the barrel 2 is hermetically sealed to the head 6, no oil can leak out, and as the said barrel is filled with oil all parts are constantly lubricated and rendered non-corrosive. The neatness and compactness of the device is readily apparent, and it lends itself to use in crowded quarters, and especially to marine use where the rolling of the boat causes the tanks of the conventional flushing mechanism to slop over. This device is also suited to hotel and hospital use where quietness of operation is paramount.

The operating mechanism of this device is entirely separate from the water supply it controls, and therefore is free from corrosion or clogging due to matter such supply water may contain.

This automatic flushing device is as near fool-proof as may be, by making it entirely automatic and allowing only one adjustment possible, namely, the one controlling the amount of water passed at one flush.

The by-pass 27 being located on the disk 24 has two valuable features; it is kept free by reseating with each operation of the device; and, it may be readily removed for inspection.

This invention lends itself to construction suitable for economical manufacture, as most of the machine work may be done in the turret lathe.

If it is desired to have the moving parts incased, this may be done by placing a stamped U channel over casting 1 to cover barrel 2 and stem 5.

The operating mechanism may be removed from casting 1 by simply unscrewing nut 14 and stem 5, and the remaining parts as readily taken apart. Casting 1 may be detached by unscrewing suitable unions at C and D, thus accessibility is attained for the entire mechanism.

I claim:

1. A valve controlling mechanism for flushing water closets comprising a body, a barrel adapted to contain a fluid axially guided by said body and rigidly fixed to a flush control valve stem, a single piston having a check valve and by-pass fitted within said barrel and operably movable relative to said barrel and body, a rod adjusting nut and lever which may connect said piston to

a bowl-seat, a spring adapted to react between said piston and said barrel and a spring adapted to react between said piston and said body.

5. 2. In a valve controlling mechanism for flushing water closets, having a body, a barrel adapted to contain a fluid axially guided by said body and rigidly fixed to a flush control valve stem, a single piston having a 10 check valve fitted within said barrel and operably movable relative to said barrel and body, a rod adjusting nut and lever connecting said piston to a bowl-seat, a spring adapted to react between said piston and said barrel, and a spring adapted to react between said piston and said body; a by-pass in said piston obtained by slotting said 15 check valve's face or seat.
3. In a valve controlling mechanism for flushing water closets, having a body, a barrel adapted to contain a fluid axially guided by said body and rigidly fixed to a flush control valve stem, a single piston having a by-pass there-through fitted within said 20 barrel and operably movable relative to said barrel and body, a rod adjusting nut and lever connecting said piston to a bowl-seat, a spring adapted to react between said piston and said barrel, and a spring adapted to 25 react between said piston and said body; a check valve in said piston formed by an enlarged portion of said rod seating in said piston and having a light spring react between an extended portion of said rod and 30 said piston substantially as set forth.
4. In a valve controlling mechanism for flushing water closets, having a body, a barrel adapted to contain a fluid axially guided by said body and rigidly fixed to a flush 35 control valve stem, a single piston having a check valve and by-pass fitted there-through within said barrel and operably movable relative to said barrel and body, a rod ad-

justing nut and lever connecting said piston to a bowl-seat, a spring adapted to react between said piston and said body; a spring compressed between a member of said barrel and said piston so that the force of said compression upon said barrel member is exerted in the direction of closure of said 50 flush control valve.

5. In a valve controlling mechanism for flushing water closets, having a body, a barrel adapted to contain a fluid axially guided by said body and rigidly fixed to a flush 55 control valve stem, a single piston having a check valve and by-pass there-through fitted within said barrel and operably movable relative to said barrel and body, a rod adjusting nut and lever connecting said piston to a bowl-seat, and a spring adapted to react 60 between said piston and said barrel; a spring compressed between a member of said body and said piston so that the force of said compression upon said piston is in the 65 direction of the opening of said flush control valve.

6. In a valve controlling mechanism for flushing water closets, having a body, a barrel adapted to contain a fluid axially guided 70 by said body and rigidly fixed to a flush control valve stem, a piston rod adjusting nut and lever connected to a bowl-seat, a spring adapted to react between said piston and said barrel, and a spring adapted to 75 react between said piston and said body; a piston axially guided on a portion of said piston rod and normally held against an enlarged portion of said piston rod.

In testimony whereof I affix my signature 80 in the presence of two witnesses.

BENJAMIN PURNELL.
